UNITED STATES PATENT OFFICE.

OTTO J. KORHUMMEL, OF CHESTER, CONNECTICUT, ASSIGNOR TO C. J. BATES & SON, OF CHESTER, CONNECTICUT, A FIRM COMPOSED OF CARLTON J. BATES AND HAMILTON C. BATES.

SCISSORS CASE.

Application filed January 26, 1923. Serial No. 614,980.

To all whom it may concern:

Be it known that I, OTTO J. KORHUMMEL, a citizen of the United States, residing at Chester, in the county of Middletown and 5 State of Connecticut, have invented a new and useful Improvement in Scissors Cases; and I do hereby declare the following, when taken in connection with the accompanying drawings and the characters of reference 10 marked thereon, to be a full, clear, and exact description of the same, and which said drawings constitute part of this application, and represent, in—

Fig. 1 a face view of a scissors-case, constructed in accordance with my invention, in the closed position.

Fig. 2 a similar view in an open position.

Fig. 3 a sectional view on the line 3—3 of Fig. 1, on an enlarged scale.

20 This invention relates to improvement in scissors-cases, and particularly to cases formed from leather, or other suitable material in the form of a sheath, into which scissors are inserted, points inward. It not 25 infrequently happens that the scissors are entered so far into the case that the points penetrate the inner end of the case. The object of this invention is to provide stops which will limit the inward movement of 30 the scissors, and the invention consists in the construction and arrangement of parts as hereinafter described and particularly recited in the claims.

In carrying out my invention, I employ a 35 case 5, formed from leather or other suitable material in the usual way, so as to form a pocket into which the scissors may be inserted. The case is provided with the usual flap 6, provided with a socket 7, to engage 40 with a ball 8. On each side of a vertical cen-

tral line and closely adjacent thereto I locate rivets 9 and 10. These rivets are preferably hollow rivets or eyelets, so as to form holes through which a cord or ribbon may be passed, by which the case may be suspended. 45 These rivets are so located that when the blades 11 of a pair of scissors are inserted into the case, the bows 12 and 13 will come to a bearing, and preferably at a point before the points reach the inner end of the 50 case, so as to prevent the points from being pushed through the inner end of the case. These rivets or stops do not interfere with the free entrance and removal of the scissors,—in fact, they hold the bows up, so as 55 to be conveniently grasped by the fingers, when the case is open.

I claim:

1. A scissors-case, including a pocket and two stops respectively located on opposite 60 sides of and closely adjacent to a central, vertical line and adapted to limit the inward movement of a pair of scissors into the case.

2. A scissors-case, including a pocket and eyelets arranged on opposite sides of the 65 center, and adapted to limit the inward movement of a pair of scissors into the case.

3. A scissors-case, comprising a pocket and closure therefor, combined with two stops respectively located on opposite sides 70 of a central line, and adapted to limit the inward movement of a pair of scissors into the said case.

In testimony whereof, I have signed this 75 specification in the presence of two subscribing witnesses.

OTTO J. KORHUMMEL.
